UNITED STATES PATENT OFFICE.

CHESTER W. FOWLER, OF EASTLAKE, MICHIGAN.

FEED-WATER HEATER.

SPECIFICATION forming part of Letters Patent No. 373,520, dated November 22, 1887.

Application filed July 6, 1887. Serial No. 243,566. (No model.)

To all whom it may concern:

Be it known that I, CHESTER W. FOWLER, a citizen of the United States, residing at Eastlake, in the county of Manistee and State of Michigan, have invented certain new and useful Improvements in Feed - Water Heaters; and I do declare the following to be a full, clear, and exact description of the invention, such as will enable others skilled in the art to 5 10 which it appertains to make and use the same, reference being had to the accompanying drawing, and to the letters and figures of reference marked thereon, which form a part of this specification.

15 This invention relates to feed-water heaters of that class which are located in the space back of the boiler and supply water to the boiler as hot or nearly as hot as the water in the boiler, and has for its object to simplify 20 the construction and produce a compact arrangement of parts, whereby the heat from the waste products of combustion is utilized to the best possible advantage and a space is left in the heater above the water-line, into which the 25 live steam is injected and the water sprayed. Ordinarily the space in the rear of the boiler is covered over by a fire-arch or a pan. When the boiler-flues are repaired, it is necessary to remove said arch, which involves considerable 30 expense, and if the pan be used instead of the arch it soon rusts out, and, besides, considerable heat is lost by evaporation. These objections are obviated by my construction, which also aims to maintain the feed-water at or near 35 the same temperature of the water in the boiler or battery of boilers, thereby separating all foreign matter from and purifying the water previous to its entrance into the boiler.

The improvements consist in the peculiar 40 construction and combination of parts, which will be presently described, claimed, and shown in the annexed drawing, which is a perspective view, parts being broken away, of an organization or plant of boilers embodying my 45 invention.

The spraying of the water in my heater keeps the boiler-connections, boilers, mud-drum, and heater of so nearly the same temperature as to prevent unequal expansion, and 50 consequent cracks and leaks. The water being forced into the heater, runs into the mud-

drum by force of gravity, and thus supplies the boilers. The steam-generator A, having the steam-drum B, is suitably incased by the brick-work C, having the usual smoke-space, 55 D, in the rear of the steam-generator, which space D is closed at the top by the feed-water heater E, having its lower portion extended into said space a short distance to expose a large heating-surface. The steam-generator 6c may be a single boiler; or, as shown, it may comprise a series or battery of boilers arranged side by side and communicating with each other by the steam-drum B, which is common to all and is placed over the series of boilers 65 and extends at right angles to their length. The feed-water heater extends across the entire length of the space in the rear of the boilers, which is from end boiler to end boiler, and is placed opposite the upper ends of the 70 boilers, so as to be above the flues and not be in the way and interfere with the ready cleaning of said flues. The mud-drum G is located at a lower level than the water-heater E, and is connected with the latter by pipe H, having 75 check-valve h. The upper end of the pipe H connects with the water-heater E at a short distance from its top, thereby leaving a steam-space, e, in the upper portion of said feed-water heater, which is supplied with steam 8c from the steam-drum B by pipe F. The water is supplied to the feed-water heater in a spray or fine jets by the spray or perforated pipe I, located within and extending the whole length of the steam-space e in the water-heater E, 85 which is provided with a suitable gage to register the pressure and height of water.

Having thus described my invention, what I claim, and desire to secure by Letters Patent, is—

1. The combination of the steam-generator, the steam-drum, the feed-water heater located in the rear of the steam-generator and closing the smoke-space, and having a portion extended above the top of the steam-generator 95 to form a steam-space in its upper portion, which is connected with the steam-drum, the spray-pipe located in said steam-space in the feed-water heater, and the mud-drum connected with the feed-water heater about on a 100 level with the top of the steam-generator, substantially as set forth.

2. The combination of the series of boilers arranged side by side and closed in, leaving a smoke-space in the rear of the series of boilers, the feed-water heater arranged opposite the top 5 of the boilers and closing said smoke-space, and provided with a steam-space above the tops of the boilers, the steam-drum common to all the boilers and connected with said steam-space in the feed-water heater by pipe to F, the spray feed-pipe located in and extending the whole length of the steam-space of the

water-heater, the mud-drum, and the pipe having a check-valve connecting the mud-drum and the feed-water heater, substantially as and for the purpose specified.

15

In testimony whereof I affix my signature in presence of two witnesses.

CHESTER W. FOWLER.
